UNITED STATES PATENT OFFICE.

GEORGE LIVINGSTON, OF PHILADELPHIA, PENNSYLVANIA.

BOX.

1,224,891.

Specification of Letters Patent.

Patented May 1, 1917.

Application filed October 14, 1916. Serial No. 125,582.

To all whom it may concern:

Be it known that I, GEORGE LIVINGSTON, a citizen of the United States, residing at Philadelphia, in the county of Philadelphia and State of Pennsylvania, have invented certain new and useful Improvements in Boxes, of which the following is a specification.

My invention consists of an improved 10 box and is particularly serviceable for use as a lunch box; however it may be used for other purposes where a portable box is required.

One object of my invention is to provide a box having a movable lid and to provide means for firmly securing the lid to the body portion of the box.

Another object of my invention is to so construct the box and the fastening means 20 that sufficient friction may be brought to bear upon the several parts in order to prevent them from being accidentally opened due to jar or vibration.

A further object of my invention is to provide a box which will be durable and can be manufactured and sold at a comparatively small cost.

Another object of my invention is to so construct the box and the fastening means 30 that the latter may be quickly and easily operated to open or lock the lid.

These objects, and other advantageous ends which will be described hereinafter, I attain in the following manner, reference 35 being had to the accompanying drawings in which—

Figure 1 is a perspective view of a box made in accordance with my invention.

Fig. 2 is an enlarged sectional view taken 40 on the line *a—a* of Fig. 1.

Fig. 3 is a fragmentary front elevation showing how the lid is secured to the body portion, and

Fig. 4 is a section on the line *b—b* of 45 Fig. 3.

Referring to the drawings, the box 1 has a body portion 2 to which is hinged at 3 a lid 4, the latter in the present instance being provided on its uppermost surface with 50 hinged handles 5, which when not in use may assume the position shown in Fig. 1.

The body portion 2 and the lid 4 is preferably made of sheet metal, the body portion having a folded upper edge 6 which terminates on the outside of the box in the form 55 of a bead 7, said bead inclosing a core 8 of

wire, the latter acting as a reinforce for said bead.

The bead 7 preferably extends entirely around the body portion and acts as a band. 60 The lid 4 terminates at its lower edge in a bead 9 which incloses a core 10 preferably of wire. The bead 9 is interrupted at 11 at the front of the box but the core 10 continues past said interrupted portion and 65 forms a pivot support for a plate 12, the latter having a curled lower end 13 and a hole 14 through which a staple 15 on the body portion 2 is designed to project.

The plate 12 is preferably made of resilient sheet metal such as spring steel or the like and has its inner surface 16 designed to engage the outer portion of the bead 7 to form frictional engagement therewith and tend to bind the lid 4 to the body 75 portion 2.

The plate 12 is operatively held in engagement with the bead 7 by means of a hook 17, the latter being pivoted and free to swing on a pivot pin 17^a attached to the 80 lid 4. The hook 17 is curved as clearly shown in Figs. 1 and 3, the engaging portion 18 of said hook being formed of a shorter radius than the distance between this curve and the pivotal axis of the hook, 85 so that the end 19 of the hook will freely pass through the staple 15 during the initial inserting movement of the hook, but a continued movement of said hook will bring the portion 18 of the hook into binding engagement with the upper portion of the staple as clearly shown in Figs. 1 and 2.

The hook 17 is also preferably bent inwardly as shown in Fig. 2 so as to engage the outer surface of the hinged plate 12, and 95 press the rear surface of said plate against the bead 7 as previously described.

It is thus understood that with my improved box, the hook 17 acts to securely engage the staple 15 and that there is additional frictional engagement between the plate 12 and the bead 7 and between the hook 17 and the plate 12.

Furthermore, the turned upper edge 6 of the body portion 2 acts as a reinforce and 105 the outer depending lap of said turned edge 6 serves to support and form a backing for the bead 7. It will be noted that the turned edge 6 fits within the lid 4 and that the bead 7 is directly below the bead 9.

In the box constructed in accordance with my invention, it is practically impossible

for the lid to become detached and furthermore the securing means is such as to prevent rattling between the lid and body portions.

5 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what 15 I claim as new and desire to secure by Letters Patent is:

1. A box comprising lid and body portions, a plate pivotally connected to one of said portions and having a hole therein, a 20 staple in the other of said portions designed to project through said hole in the plate, and a hook mounted on one of said portions and designed to extend across the parting between said portions and having a hooked 25 end adapted to pass through said staple, substantially as described.

2. A box comprising lid and body portions, one of said portions having a bead including a reinforcing core, said bead being 30 interrupted in its length, a plate hinged to said core in the space provided by said interruption and having a hole therein, a staple in the other of said portions designed to project through the hole in said plate, 35 and a hook movably secured to one of said portions and designed to extend across the parting between said portions and having a hooked end adapted to pass through said staple, said hook, when in said staple, being 40 operative to press the plate into frictional contact with the box, substantially as described.

3. A box comprising lid and body por-

tions, one of said portions having a bead including a reinforcing core, said bead being 45 interrupted in its length, a plate hinged to said core in the space provided by said interruption and having a hole therein, a staple in the other of said portions designed to project through the hole in said plate, a 50 bead formed on said latter portion and designed to be engaged by said plate, and a hook movably secured to one of said portions and designed to extend across the parting between said portions and having a 55 hooked end adapted to pass through said staple and to press said plate into frictional engagement with said latter bead, substantially as described.

4. A box comprising lid and body portions, said lid having its lower edge terminating in a bead, a core for said bead, said bead being interrupted in its length, said core extending across the space provided by said interruption, a plate pivotally mounted 60 on said core and extending within said space, said plate having a hole therein, a staple on the body portion designed to project through said hole, said body portion having a turned upper edge, a portion of 70 which fits within said lid, the outer lap of said turned edge depending and terminating in a bead below the bead of said lid, and a hook pivotally secured to one of said portions and designed to extend through said 75 staple and to move said plate into frictional engagement with said bead on the body portion, substantially as described.

In testimony whereof I have signed my name to this specification in the presence of 80 two subscribing witnesses.

GEORGE LIVINGSTON.
